Attns.

UNITED STATES PATENT OFFICE

CECIL JAMES BLAKE, OF MANCHESTER, NEW HAMPSHIRE, ASSIGNOR TO J. HAMMOND STEWART, OF LYNN, MASSACHUSETTS

COUNTER MACHINE WITH FLANGE PLATE WAXING MEANS

Application filed October 31, 1930. Serial No. 492,440.

The present invention relates to machines for applying such substances in connection with the molding operation itself, and supplying the lubricant only at the place where it is needed, with exclusion from those parts of the counter where its presence is objectionable. It is the object and accomplishment of my invention to provide such means in combination with counter molding instruments and particularly the flange turning plate of a counter molding apparatus.

In the standard type of counter molding machine, the counter blank, which is ordinarily first moistened or tempered with water to make it pliable, is gripped between an inner mold member, known as the plug or last, and a pair of outer members known as molds, which shape the counter to the prescribed form and squeeze it with great force. At this time the counter blank is so placed that a zone along one edge, of a width sufficient to provide the flange of the finished counter, protrudes from between the plug and molds, extending outward from the front faces thereof, which are in a plane. A flange turner plate or presser, commonly called a flange plate, is caused to wipe across these faces of the plug and molds while the counter blank is so gripped, and in so doing to bend the protruding edge of the blank over to form the flange, at the same time pressing the flange with great force against the contiguous face of the plug, in the case of an in-turned flange, or of the molds in the case of an out-turned flange.

It is desirable to provide lubricant between the contacting surfaces of the counter blank and flange plate, in order to cause the flange plate to pass over the counter flange smoothly and without chattering, to avoid tearing or unduly stretching the flange, and to prevent the plate from adhering to the flange and bending it back or crumpling it in the return stroke. It is also desirable to limit the application of lubricant on the counter to the flange portion thereof alone, leaving the body of the counter in good condition to receive and hold adhesive which is used in the shoe making process to stick the upper leather and lining to the opposite sides of the counter. While it has been common heretofore to apply oils, waxes and the like to counter blanks prior to molding, no means have been known

otherwise of a well known standard design is herein shown for illustration, and with the understanding that the essence of the invention and the generic protection herein claimed is not limited thereby to such machine.

Referring to the drawing,—

Fig. 1 is a front elevation of so much of a standard counter molding machine, having my invention applied thereto, as suffices to illustrate the invention;

Fig. 2 is a vertical section taken on line 2—2 of Fig. 1;

Figs. 3 and 4 are perspective views of the parts of an attachment to the machine by which wax is delivered to the flange plate.

Like reference characters designate the same parts wherever they occur in all the figures.

In the drawing, *a* represents the top cross beam or stationary cross head of the machine, which is rigidly supported and held at a fixed distance from the base by upright tie rods *b* and nuts *c* thereon. *d* indicates the so-called plug or last forming the inner molding instrument, and *e*, *e* designate the molds or outer molding instruments by which the counter is shaped and gripped with its edge protruding forwardly. *f* is the so-called flange plate or flange turning presser, and *g*, *g* are the guides, secured to the cross beam *a*, by which the flange plate is guided to move in a plane parallel to the plane front faces of the plug and molds, and held so as to apply pressure forcibly against the flange which

is turned over by its action as it wipes across these faces. *h* is a link forming part of the mechanism by which the flange plate is operated.

8 These mechanisms are constructed, arranged and operated according to the standard practice and substantially as illustrated in patents to Stewart, No. 467,473, January 19, 1892, and No. 826,697, July 24, 1906.

10 The new step of this invention is embodied in means for automatically supplying wax to the contacting surfaces of the flange plate and counter, and in the present embodiment, it applies the wax directly on the rear face

15 of the flange plate. A supply of a liquid preparation of wax is held in a cup or reservoir *j* and is conducted by gravity through a conduit *k* to a wick *l*, or equivalent wiper or spreader, located beneath the cross beam and

20 directly above the molds, and behind the flange plate. This spreader distributes the wax over so much of the surface of the flange plate as comes into contact with the counter flange; or at least, and particularly, over the

25 part which first engages the flange.

In this illustration the molding instruments are arranged to form an inturned flange on the counter with pressure by the flange plate against the forward side of plug *d*.

30 The flange plate first engages the counter at the rear end of the latter, in the course of its down stroke from a raised position. The wax spreader *l* is so located with respect to the total travel of the flange plate as to apply wax to that part of its surface which first comes to bear forcibly on the counter flange.

The wax spreader is preferably, though not necessarily, a wick made from a piece of thick felt partially embraced by an open sided box

40 or tray *m*, the latter in turn being fitted slidably within a box *n* which is open at its forward end and has slotted flanges *o* at opposite sides for attachment to the beam *a*. A hole *p* in the top wall of the box *n* registers with

45 the wax conduit to admit wax to the spreader. The tray *m* is open at the top, to leave the wick exposed for reception of wax in any part of its upper surface. Springs *q* are interposed between the rear wall of the tray

50 and the rear wall of the box *n*.

This box is in effect a holder and guide for the wick, so made as to afford an abutment for the springs *q* and to confine any excess of the wax delivered, as well as the permit detachable connection with the cross beam of the machine. The springs contain a sufficient contact of the wick or spreader at all times with the back of the flange plate. The tray *m* affords by its rear wall a rigid member for

55 taking the thrust of the springs and transmit thrusts uniformly to the spreader wick. Its bottom and side walls relieve the wick of substantially all rubbing contact on the enclosing guide.

60 Preferably the conduit for the wax is

formed in part as a passage through the cross beam *a*, or as a tube placed in such a passage; although it would not be a departure from the invention to locate the supply reservoir at any other convenient point and lead the conduit to the spreader in any other convenient course.

70 It will be understood that various modifications and departures from the illustration herein given may be made without departure from the principles of this invention, and that all such modifications are intended to be protected by the more generic of the appended claims. It is to be noted also that the naming of wax in the foregoing specification as the lubricant to be used, is not intended as a limitation of the invention to the use of any specific lubricant or class of lubricants. "Wax" is a descriptive term typifying all lubricants which are suitable to be used for the purpose, and are capable of being applied in the manner, indicated in this specification.

75 The device as shown is adapted to be applied readily to counter molding machines already in use. The slotted flanges on the

spreader holding device are adapted to be slipped under the heads of bolts which are provided on such machines for securing the reaction plate for the outer molds to the cross beam. The wax cup may be mounted on a bracket which can be attached to the cross beam by a bolt as shown, or may be provided with a slotted base flange, similar to the flanges *o*, and passed under the head of one of the bolts which in the standard machines secure the bracket for the flange plate operating rocker. Or the conduit *k* leading from the cup may itself be the support for the cup, being in that case made sufficiently strong and rigid, and being rigidly secured in the passage through the beam. Such passage may be drilled in any location desired, for instance, or at an inclination as well as vertically, and may lead on a straight slant from the location of the cup to the receiving hole in the spreader guide. However, the generic principles of the invention may be otherwise incorporated in counter molding machines of other designs.

100 110 115 What I claim and desire to secure by Letters Patent is:

1. The combination with counter molding instruments including a flange turning presser, of means for automatically delivering lubricant between the contacting faces of said presser and that portion of the counter which is engaged thereby.

120 125 130 2. The combination with means for holding a shoe counter and means for turning and pressing a flange thereon, of means for automatically supplying lubricant between such flange and the turning and pressing means.

3. A counter molding machine having a flange turning presser and means for applying

ing lubricant to the flange engaging face thereof.

4. A counter molding machine including complementary molding instruments adapted to shape a counter blank and grip it with one edge protruding, in combination with a flange plate arranged to wipe over, bend into a flange and press such protruding part, and automatic wax supplying means arranged to deliver wax between the contacting surfaces of said flange plate and the counter blank.

5. A counter molding machine comprising a frame, molding instruments, a cooperative flange plate, and a spreader arranged to apply wax to the wiping face of said flange plate in the course of its normal travel.

6. A counter molding machine comprising a frame, molding instruments, a cooperative flange plate, a spreader arranged to apply wax to the wiping face of said flange plate in the course of its normal travel, a wax reservoir, and a conduit arranged to conduct wax continuously from the reservoir to the spreader.

7. In a counter molding machine, a beam forming part of the frame of such machine, a flange plate mounted to reciprocate across said beam, a wick box attached to the under side of the beam, and a wick contained in said box and protruding therefrom to bear on the adjacent face of the flange plate.

8. In a counter molding machine, a beam forming part of the frame of such machine, a flange plate mounted to reciprocate across said beam, a wick box attached to the beam, a wick contained in said box and protruding therefrom to bear on the adjacent face of the flange plate, and provisions for delivering liquid wax continuously into said wick box.

9. A wax applying attachment for counter molding machines comprising a box open at one end and having apertured flanges by which such attachment may be made, a tray slidably contained in said box, spring means interposed between the closed end of the box and said tray for projecting the latter toward that element of the machine on which wax is to be applied, and a wick in said tray adapted to be protruded from the box by the spring.

In testimony whereof I have affixed my signature.

CECIL JAMES BLAKE.
